UNITED STATES PATENT OFFICE

155,902

DESIGN FOR A COLLAPSIBLE BOAT HOUSE
TRAILER WITH REMOVABLE ROOF

Harry S. Keating, Toledo, Ohio

Application July 25, 1947, Serial No. 140,506

Term of patent 14 years

(Cl. D14—3)

To all whom it may concern:

Be it known that I, Harry S. Keating, a citizen of the United States, residing at Toledo, in the county of Lucas and State of Ohio, have invented a new, original, and ornamental Design for a Collapsible Boat House Trailer With Removable Roof, of which the following is a specification, reference being had to the accompanying drawing, forming part thereof.

In the drawing, Figure I is a side perspective view of the collapsible boat house trailer with removable boat roof portions of the coupling member being broken away for convenience of illustration;

Figure II is a side elevational view of the boat house trailer set up for use; the other side of the design being substantially the same as the side illustrated in Figure II;

Figure III is an end view of the collapsible boat house trailer with removable boat roof;

Figure IV is a top plan view of the boat house trailer while Figure V is a front elevational end

view, the coupling member being omitted for sake of convenience in illustration in both Figures IV and V.

The characteristic features of my design reside in the portions shown by means of full lines in the drawing.

I claim:

The ornamental design for a collapsible boat house trailer with removable roof, substantially as shown and described.

HARRY S. KEATING.
